UNITED STATES PATENT OFFICE.

JOHN G. MAGIN, OF ROCHESTER, NEW YORK, ASSIGNOR TO HENRY CONOLLY COMPANY,
OF ROCHESTER, NEW YORK, A CORPORATION OF NEW YORK.

LOOSE-LEAF BINDER.

1,083,021.

Specification of Letters Patent.

Patented Dec. 30, 1913.

Application filed October 30, 1912. Serial No. 728,657.

To all whom it may concern:

Be it known that I, JOHN G. MAGIN, of Rochester, in the county of Monroe and State of New York, have invented a new and useful Improvement in Loose-Leaf Binders, which improvement is fully set forth in the following specification and shown in the accompanying drawings.

The present invention relates to loose leaf binders, and an object thereof is to provide a simple and inexpensive construction in which there is employed a transfer member for moving the leaves from and placing them on suitable impaling means, the said transfer member being adapted to be supported in such a manner that it may be utilized for receiving and supporting the leaves independently of the impaling means, thus permitting the leaves to be transferred singly from the impaling means to the transfer member or vice versa.

To these and other ends the invention consists in certain parts and combinations of parts all of which will be hereinafter described, the novel features being pointed out in the appended claims.

In the drawings: Figure 1 is a perspective view of the binder with the leaves removed and the retaining means disconnected from the impaling means and the transfer member; Fig. 2 is a transverse section through the binder with the leaves therein; Fig. 3 is a sectional view illustrating the transfer member supported by the retaining means; Fig. 4 is a side view of the binder with the transfer member supported by the retaining means; and Fig. 5 is a transverse section through the binding means of the binder when the latter is closed.

In the illustrated embodiment of the invention, there is provided a pair of cover members 1 and 2 hinged to connecting members 3 and 4 respectively which in turn are hinged to a single back piece 5. In the present instance, the connecting members 3 and 4 serve for supporting the binding means. With the foregoing in view, the connecting piece 4 embodies a flat metallic bar 5 from the inner side of which projects the impaling means consisting of one or more impaling projections 6 for receiving the leaves 7, the latter being provided with openings 8 through which the impaling projections 6 extend. The connecting piece 3 carries the retaining means for cooperating with the

projections 6 in order to hold the leaves thereon. In this instance, this retaining means embodies a casing 9 in which is arranged a locking member 10, preferably, in the form of a slide-bar moved in one direction under the action of a spring 11 and in the other direction through the medium of a finger piece 12 projecting from one end of the casing 9. The casing 9 may be formed on its inner face with openings 13 through which the ends of the projections 6 may be extended in order that the shoulders 14 on said projections 6 may be engaged by shoulders 15 on the locking member 10 so as to hold the connecting piece 3 to the projections 6.

Embodied in the binder is a transfer member through the medium of which any number of leaves may be removed at one time from the impaling projections and again fitted to the impaling projections without disturbing the alinement of the openings 8 in the leaves. This transfer member, in this instance, embodies a bar 16 having two transfer projections 17 extending from one side thereof to enter openings 18 in the leaves and hold the latter against relative movement in their planes, the bar serving to support the leaves on the projections 17 when the leaves are removed from the projections 6.

It has been found that a binder of a type hereinbefore described has superior advantages if means be provided for supporting the transfer member with its transfer projections or projection upright, as it is then possible to transfer the leaves, one at a time, from the impaling projections to the transfer projections or vice versa, thus adapting the binder for use as a ledger in connection with typewriting machines and more particularly book-type-writing machines.

In this embodiment, the transfer member is adapted to be supported upon the connecting member which carries the retaining means, the latter preferably also acting to support the transfer member. To this end, the transfer member is provided with one or more projections 19 extending from that side of the plate 16 opposite the side from which the projections 17 extend, being preferably formed integrally with said projections 17. These projections 19 have shoulders 20 and are adapted to extend through

openings 21 in the inner face of the casing 9 so that the shoulders 20 may be engaged by shoulders 22 on the locking member 10, and, in this way, hold the projections 17 upright when the binder is open as in Fig. 4. The cover pieces 1 and 2 will then serve as supports and protectors for any leaves arranged on the projections 6 and 17 so that the leaves may freely be transferred from one of said sets to the other for making entries on the individual sheets, and, when work in the book has been completed, the leaves on the two sets of projections may be immediately brought together without any further work on the part of the user.

The devices for accomplishing the foregoing results are simple in operation and require the addition of but few parts to the ordinary binder so that the cost of the manufacture of the binder is not materially increased.

What I claim as my invention and desire to secure by Letters Patent is:

1. In a loose leaf binder, the combination with a pair of cover members, connecting pieces hinged to the cover members, and a back piece to which the connecting pieces are hinged, of impaling means carried by one of the connecting pieces, retaining means arranged on the other connecting piece for coöperating with the impaling means, a transfer bar having a transfer projection extending laterally therefrom for coöperating with leaves on the impaling means, and means, arranged on the connecting piece carrying the retaining means, for supporting the transfer bar with its transfer projection extending upwardly when the retaining means is disengaged from the impaling projection.

2. In a loose leaf binder, the combination with impaling means, and a member coöperating with said impaling means for retaining leaves on said impaling means, of a transfer bar having a projection for coöperating with the leaves on the impaling means, and means on the member carrying the retaining means for supporting said transfer bar when the retaining means is disconnected from the impaling means.

3. In a loose leaf binder, the combination with a member having a pair of impaling projections, and a member having a locking bar for coöperating with the impaling projections to hold the leaves on said projections, of a transfer bar independent of the first two named members and having a projection extending laterally therefrom for coöperating with the leaves on the impaling projections, and also having means adapted to be engaged by the locking member in order that the transfer projection may be held upright when the locking member is disengaged from the impaling projection.

4. In a loose leaf binder, the combination

with a member having impaling projections extending therefrom, and a member having a locking member movably arranged thereon and adapted to coöperate with the impaling projections to hold leaves on the latter, of a transfer member embodying a bar having projections extending from opposite sides thereof, the projections on one side serving to support the leaves when they are removed from the impaling projections, and the projections on the other side being adapted to be engaged by the locking member to hold the first named projections upright.

5. In a loose leaf binder the combination with a member having impaling projections extending from one side thereof and provided with shoulders near their ends, and a second member having a casing provided with openings adapted to receive the impaling projections and also having a locking member movably arranged within said casing to engage the shoulders on the impaling projections, of a transfer member embodying a bar having projections extending from opposite sides thereof, the projections on one side being adapted to receive leaves from the impaling projections, and the projections on the other side having shoulders and adapted to be passed through openings in the casing in order to be engaged by the locking member.

6. In a loose leaf binder, the combination with a pair of cover members, connecting members to which the cover members are hinged, and a back piece to which the connecting members are hinged, of impaling projections extending inwardly from one of the connecting members, a casing carried by the other cover member and provided with openings through which the impaling projections are adapted to be passed, a locking member arranged in said casing and adapted to coöperate with the impaling projections, and a transfer member having a transfer projection adapted to be passed through the leaves on the impaling projections and having portions adapted to be engaged by the locking member in order to support the transfer member upright when the locking member is disengaged from the impaling projections.

7. In a loose leaf binder, the combination with a pair of cover members, a pair of connecting members to which the cover members are hinged, and a back piece to which the connecting members are hinged, of impaling projections extending from one of said connecting members, a locking member arranged on the other of said connecting members for coöperating with the impaling projections, and a transfer member having projections extending from opposite sides thereof, the projections on one side being adapted to coöperate with the leaves on the

impaling projections and the projections on the other side being adapted to be engaged by the locking member.

8. In a loose leaf binder, the combination with a pair of cover members, a pair of connecting members to which the cover members are hinged, and a back piece to which the connecting members are hinged, of impaling means on one of said connecting members, retaining means on the other of said connecting members, for coöperating with the impaling means, and a transfer bar independent of the impaling means and the retaining means, having provision for being connected to the connecting member that carries the retaining means, when the latter is disconnected from the impaling means and also having a transfer projection extending laterally from the bar.

20 9. In a loose leaf binder, the combination with a pair of cover members, a pair of connecting members to which the cover members are hinged, and a back piece to which the connecting members are hinged, of impaling means arranged on one of said connecting members, locking means carried by the other connecting member for coöperating with the impaling means, and a transfer member having projections extending therefrom for engaging with the locking means when the latter is disconnected from the impaling means.

10. In a loose leaf binder, the combination with a pair of binder members, one of which has a rigid impaling projection and the other of which has means for releasably engaging the impaling projection, and is also provided with an opening, of a transfer member having a lateral projection for coöperating with leaves on the impaling projection and also has a projection for fitting in the opening in the last mentioned binding member.

11. In a loose leaf binder, the combination with a pair of binding members, one of

which is provided with impaling means, and the other of which is provided with an opening and means for releasably engaging the impaling means, of a transfer member having oppositely extending projections, one of which is adapted to coöperate with leaves on the impaling means and the other of which is adapted to enter the opening in the binder member to support the transfer member.

55

12. In a loose leaf binder, the combination with a pair of binder members, one of which is provided with impaling means and the other of which has means for releasably engaging the impaling means, of a transfer bar having a laterally extending projection, and coöoperating portions on the transfer bar and the binder member with the engaging means, said portions holding the transfer bar to said binder member with the lateral projection upright.

60

13. In a loose leaf binder, the combination with a pair of binder members, one of which is provided with impaling means, of a transfer member having a transfer projection, and locking means carried by the other binder member and adapted to engage both the transfer member and the impaling means.

70

14. In a loose leaf binder, the combination with a pair of binder members, of a rigid impaling projection permanently secured to one of said members, locking means secured to the other member and adapted to releasably engage the impaling projection, and a transfer member for coöperating with leaves on the impaling means, said transfer member also having a portion adapted to be engaged by the locking means when the impaling projection is engaged and also disengaged from the locking means.
